(57) **CLAIM**

The ornamental design for a weighted swing training apparatus, as shown.

DESCRIPTION

FIG. 1 is a perspective view of a weighted swing training apparatus showing my design;

FIG. 2 is a front elevational view of the weighted swing training apparatus;

FIG. 3 is a rear elevational view of the weighted swing training apparatus;

FIG. 4 is a right side elevational view of the weighted swing training apparatus;

FIG. 5 is a left side elevational view of the weighted swing training apparatus;

FIG. 6 is a top plan view of the weighted swing training apparatus; and,

FIG. 7 is a bottom plan view of the weighted swing training apparatus.
